(57) **CLAIM**

(21) Appl. No.: **29/339,600**

We claim the ornamental design for a coaxial cable connector,
as shown and described.

(22) Filed: **Jul. 2, 2009**

DESCRIPTION

(51) **LOC (9) Cl.** **13-03**

FIG. 1 is a perspective view of a new coaxial cable connector;
FIG. 2 is a side elevation view thereof, with the opposite side
elevation view being a mirror image thereto;

(52) **U.S. Cl.** **D13/151**

FIG. 3 is a top plan view thereof; and,

(58) **Field of Classification Search** D13/133,
D13/149, 151, 154, 184, 199; 439/13, 20,
439/22, 133, 135, 246, 306, 321, 322, 480,
439/476.1, 578, 583, 584, 585, 668

FIG. 4 is a bottom plan view thereof.

See application file for complete search history.

The broken line portion of the figure drawings is included to
show unclaimed subject matter only and forms no part of the
claimed design.
